UNITED STATES PATENT OFFICE.

WILLIAM MELAS, OF PHILADELPHIA, PENNSYLVANIA, ASSIGNOR OF ONE-HALF TO
DAVID TOWNSEND, OF PHILADELPHIA, PENNSYLVANIA.

OIL-BURNER.

1,144,719.

Specification of Letters Patent. Patented June 29, 1915.

Application filed March 5, 1914. Serial No. 822,553.

To all whom it may concern:

Be it known that I, WILLIAM MELAS, a citizen of the United States, residing in the city and county of Philadelphia, State of Pennsylvania, have invented a new and useful Oil-Burner, of which the following is a specification.

My invention consists of a burner for liquid fuel, in which the fuel is presented to a current or blast of the diluent, which may be air, steam or other fluid of substantially gaseous form under pressure, in a more or less comminuted form and distributed over a surface of an area comparatively great in proportion to the volume of fuel.

It further consists of such a burner in which the area of contact of the diluent with the fuel is large in comparison with the volume of the latter.

It further consists of such a burner in which the area of the fuel emission is comparatively small but of comparatively large longitudinal extent.

It further consists of such a burner in which the area of fuel emission is less than the area of contact with the diluent.

It further consists of such a burner in which the area of fuel emission is variable in accordance with the pressure of such fuel.

It further consists of such a burner in which the fuel is distributed over a comparatively large surface for contact with the diluent.

It further consists of such a burner in which the area of fuel emission is automatically controlled between zero and predetermined maximum area by increase and decrease of the fuel pressure.

It further consists of such a burner in which a fuel feeding body is formed with fuel outlet throughout its length and surrounded by a chamber having an inlet for the diluent at one end.

It further consists of such a burner in which a fuel feeding body is formed with a longitudinally extending fuel outlet expandable and contractible according to the fuel pressure and surrounded by a chamber having an inlet for the diluent at one end.

It further consists of such a burner having a fuel-feeding body formed with a helical slot.

It further consists of such a burner

formed with a tightly coiled helix having a fuel inlet at one end. 55

It further consists of such a burner having a fuel-feeding body formed from a tightly coiled helical wire having one end closed and having an inlet in the opposite end. 60

It further consists of such a burner having a fuel-feeding body formed with a tightly-coiled wire helix closed at one end and having fuel inlet at the opposite end, and a casing surrounding such body to form 65 a chamber open at one end and having an inlet for the diluent at the opposite end.

It further consists of other novel features of construction, all as will be hereinafter set forth. 70

The annexed drawing and the following description set forth in detail one mechanical form embodying the invention, such detail construction being but one of various mechanical forms in which the principle of 75 the invention may be used.

In said annexed drawings—Figure 1 represents an axial section of my improved burner. Fig. 2 represents a side view of the oil feeder. Fig. 3 represents a transverse 80 section of the burner on the line $x-x$, Fig. 1. Fig. 4 represents a transverse section on the line $y-y$, in Fig. 1. Fig. 5 represents an axial section of another form of burner embodying my invention. Fig. 6 represents a 85 side view of the oil-feeder. Fig. 7 represents a transverse section of the burner on the line $z-z$ in Fig. 5. Fig. 8 represents an axial section of still another form of burner embodying my invention. Fig. 9 represents 90 a side view of the oil-feeder. Fig. 10 represents an axial section of a further form of burner embodying my invention. Fig. 11 represents a side view of the oil-feeder. Fig. 12 represents a transverse section on the line 95 $w-w$ in Fig. 10.

Similar numerals of reference indicate corresponding parts in the figures.

Referring to the drawings, the reference numeral 1 indicates a casing, preferably of cast metal and formed with a tubular and laterally-projecting socket, 2, to which a pipe or similar conduit conveying liquid fuel can be secured, and a laterally-projecting tubular nipple, 3, to which a pipe or similar 100 conduit conveying air, steam, or other 105 conduit

diluent under pressure can be secured. The casing is formed with an axial chamber or bore, 4, the outer end, 5, of which is preferably flared, that end of the casing forming 5 the nozzle of the burner. An enlargement or chamber, 6, continues said bore and has the diluent-inlet, 7, opening into it, and said enlargement is continued into an enlargement or cylindrical fuel-chamber, 8, of 10 greater diameter, into which a fuel-inlet, 9, opens, and forming a beveled shoulder or seat, 10, at the juncture of said chambers. A bore, 11, of still greater diameter is formed to the rear of the fuel-chamber and has an 15 internally screw-threaded rear-portion, 12, into which the threaded-portion, 13, of a screw-plug, 14, having a pin, 15, upon its inner end is screwed.

A fuel-feeder is axially supported within 20 the axial bore 4 and the diluent-chamber 6, and consists of a helix, 16, of tightly coiled wire, 17, having a plug, 18, preferably outwardly pointed, in the outer end of the fuel-duct formed therein, and closing the same, 25 and a head, 19, having a reduced portion, 20, fitted in the inner end of the helix to close the same, a body, 21, fitted in the inner end of the diluent-chamber, and an annular beveled flange, 22, seated upon the beveled an- 30 nular seat at the juncture of the two cham- bers. Said head has an axial bore, 23, which communicates with the fuel-chamber and the interior of the helix to form a fuel-channel into the latter. A coiled spring, 24, upon 35 the pin of the screw-plug and within the fuel-chamber, bears against said plug and the inner head of the fuel-feeder, holding the flange of the latter tightly against its seat. An annular, narrow and elongated atomiz- 40 ing and mixing chamber, 25, is formed be- between the fuel-feeder and the axial bore of the burner-casing which parts form the walls of such chamber, communicating at its inner end with the diluent supply and having 45 its outer end constituting the burner-nozzle.

In the form illustrated in Figs. 5, 6, and 7 of the drawings, the casing, 1, has the diluent-nipple 3 and the diluent inlet 7 into the diluent-chamber 6, and the axial bore 4, having in this form a considerably flared outer end, 26, forming the spray-nozzle from the restricted atomizing and mixing chamber 25. The casing has the fuel inlet-nipple 2 and the fuel-inlet 9 opening into the fuel- 50 chamber 8, the rear end of which has the screw-threaded portion 12, into which the threaded portion 13 of the screw-plug 14 fits. All of these elements are substantially 55 the same as the corresponding elements in the form illustrated in Figs. 1, 2, 3, and 4.

The fuel-feeder in this form has the helix 16 formed from the tightly wound coil of wire 17 to form the narrow and elongated atomizing and mixing chamber 25, being 60 axially supported within the bore of the cas-

ing, but the outer head, 27, of this feeder is outwardly flaring to correspond to the flaring nozzle-opening 26 of the bore. The inner head, 28, of the fuel-feeder has its outer end, 29, reduced and fitted in the inner 70 end of the fuel-duct of the helix, and fits in a bore, 30, in the casing between the diluent-chamber and the fuel-chamber, and the inner end, 31, of said head is screw-threaded. A nut, 32, within the fuel-chamber and bearing against a shoulder, 33, in the outer end of said chamber is screwed upon said threaded portion of the head, and has transverse nicks, 34, in its inner face for the application 75 of a key for turning it, and the rear end of the head is also formed with diametrical nicks, 35, for the application of a screw driver or similar tool for rotating said head. 80

In the form illustrated in Figs. 8 and 9, the casing 1 is formed with an outwardly flaring conical bore, 36, the inner end of which communicates with the diluent-chamber 6, into which the inlet 7 of the nipple 3 for the diluent opens. Said chamber is continued by a screw-threaded bore, 37, the inner end of which communicates with a chamber, 38, of greater diameter, which communicates with a fuel-chamber, 39, of still greater diameter, and into which the fuel inlet 9 of the nipple 2 opens, the end 40, of which chamber is internally screw-threaded. The fuel feeder in this form of burner is conical and the helix 16^a is in the shape of an outwardly-flaring cone, having a cup-shaped head, 41, closing its wide outer end, and shaped to have its conical flare corresponding to that of the bore, so that the atomizing and mixing chamber 25^a will be outwardly flaring and conical and of the same depth throughout its length. A core, 42, outwardly-flaring and conical to correspond to the flare of the helix and the atomizing and mixing chamber, is located within the helix to form an outwardly flaring and conical fuel-duct, 43, within said helix, and the inner end, 44, of said core forms a head, fitting in the inner and smaller end of the helix. A screw-threaded shank, 45, extends inward from said head and has an axial bore, 46, open at its inner end and opening at its outer end through outwardly diverging channels, 47, at the inner end of the core into the conical fuel-duct between the latter and the helix. A lock-nut, 48, upon the shank bears against the inner wall of the diluent chamber. A nut, 49, fits upon the threaded shank and bears against the inwardly-facing wall of the chamber 38, and has transverse nicks, 50, in its face for the application of a key or similar tool for turning it. The end of the shank of the core has nicks, 51, for the application of a screwdriver or similar tool for turning it. A screw-plug, 52, is screwed into the threaded portion of the fuel-chamber and has an 95 100 105 110 115 120 125 130

axial recess, 53, to accommodate the end of the shank.

In the form illustrated in Figs. 10, 11, and 12, the casing 1 has the axial bore 4 formed with the slightly flared outer end 5 of a proportionately larger diameter than the bore in the form illustrated in Figs. 1, 2, 3, and 4. The casing has the nipples 2 and 3 for fuel and diluent, opening through the fuel-inlet 9 and diluent-inlet 7, respectively, into the fuel-chamber 8 and diluent-chamber 6. The helix 16^b is located in the bore 4 and forms the atomizing and mixing chamber 25^b, like that in the form illustrated in Figs. 1 to 4, but an annular head, 54, is fitted in the outer end of said helix and has an outwardly-flared central bore, 55, the inner end of which is rabbeted, at 56, to receive the forward end of an inner helix, 57, similar to but of smaller diameter than the helix, 16^b, an annular fuel-duct, 58, being formed between said helices. The head 19^b has the reduced portion 20 fitting into the inner end of the outer helix 16^b, and has the body 21, and the beveled flange 22, bearing against the beveled annular shoulder 10, and the coiled spring 24 in the fuel-chamber bears against the head and the threaded portion 13 of the screw-plug 14 in the internally threaded end 12 of the fuel chamber, all similar to the corresponding parts of the above-referred to form. The head has longitudinal bores or channels, 59, for conveying fuel from the fuel-chamber to the inner end of the annular fuel-duct between the helices. The head has an axial bore, 60, and radiating passages or ports, 61, extend from said bore in the reduced portion of the head, to form communication between the diluent-chamber and such bore. The inner portion, 62, of the axial bore is screw-threaded, and the correspondingly threaded portion, 63, of a rod, 64, fits therein, the rod having a head, 65, at its end formed with a nick, 66, or other provision for a screwdriver or other tool for turning it and projecting into a recess, 67 in the end of the screw-plug. Said rod has a reduced portion, 68, extending from the radial air-ports 61, axially through the inner helix, and has a pointed outer end, 69, in the flaring bore of the annular outer head, and a longitudinal annular atomizing and mixing chamber, 70, is formed between the rod and the inner helix.

In practice, the fuel-inlet is connected to a source of liquid fuel, preferably under a head produced by gravity or by pressure upon the liquid, and the diluent-inlet is connected to a source of a diluent, such air under pressure, steam, or other fluid in substantially gaseous form. The nozzle of the burner is supported in a twyer of a furnace or otherwise supported where its flame is to be directed. The fuel passes into the fuel-

duct in the interior of the fuel-feeder and seeps through the helical slot formed by the helical wire and forming a continuous restricted fuel inlet of helical form into the atomizing and mixing chamber, where the current of the diluent will strike the attenuated and divided body of fuel, atomizing the same and mixing with it, and conveying the mixture out through the nozzle, where it is ignited and consumed. The helical slot will be expanded and contracted from and to zero width in proportion to the pressure upon the fuel and the impact of the diluent in the atomizing and mixing chamber, so that the supply of fuel into said chamber will be automatically regulated by the demand made upon the mixture. As the diluent and mixture pass along the atomizing and mixing chamber and over the attenuated and divided body of fuel fed into the same, the mixture becomes continuously richer by absorbing the atomized fuel, and the diluent is continuously charged with fuel throughout its passage through the burner. While the helical slot between the coils of the helix is comparatively narrow, being closed when at rest and widening during demand, the surface over which the attenuated body of fuel is spread and exposed to the current of the diluent is large compared with the size of the burner, as such slot, if drawn into a straight line, will be of considerable length compared with its longitudinal extent when in its helical form. The area of contact in this form of feeder between the diluent and the fuel will thus, proportionate to the size and capacity of the burner, be much greater than in the usual type of injector burner, and the mixture of diluent and comminuted fuel will be more intimate and complete in the present form of burner than in a burner of the injector type. In the present instance the helical slot will automatically enlarge and contract in width due to the pressure of the liquid fuel, from zero to whatever the capacity of longitudinal expansion of the helix is, so that when the supply pressure has been fixed or set, the volume of fuel discharged from the feeder will be constant. This is an important feature, since the density of liquid fuel will sometimes vary as well as impurities will sometimes pass into the feeder with the fuel, and should a portion of the helical slot become clogged, the fluid pressure in the feeder itself will increase, due to the smaller discharge area, and thus this increased pressure in the feeder will expand the helix and thus increase the discharge area sufficiently to provide for the same volume of fuel to be discharged. Should this expansion be sufficient to increase the width of the helical slot to permit the passage of the impurities, then the pressure in the feeder will imme-

dately decrease after the impurities have passed through and the helix will automatically contract and reduce the discharge area to the proper size to discharge the volume for which the burner was originally set.

By presenting a highly attenuated body of fuel over a comparatively large area to the action of a current or blast of diluent, a comparatively large contact of the diluent with the fuel is attained, with consequent fine comminution of the fuel—in the mixture.

In the form illustrated in Figs. 1 to 4, the jet of mixture leaves the nozzle substantially straight and forms a comparatively concentrated flame. The jet of mixture and, consequently, the flame in the form illustrated in Figs. 5, 6 and 7, is spread by the flaring nozzle and head into conical form.

In the form illustrated in Figs. 8 and 9, the mixture receives a conical spread within the burner and passes out to form an acute conical flame. The conical core within the conical helix fills the greater part of the interior of the latter, so that such interior will not need to be filled with fuel before the action of the helix takes place, but the conical fuel-duct, only, needs to be filled. Filling the entire space within the helix would be liable to cause too wide opening of the helical slot in the feeder and flooding of the burner.

In the burner illustrated in Figs. 10, 11 and 12, two helices are employed, the outer helix feeding the fuel outward into an atomizing and mixing chamber, and the inner helix feeding the fuel inward into another atomizing and mixing chamber, both helices forming an annular fuel-duct discharging outward and inward, whereby the capacity of the burner is nearly doubled with a proportionally slight increase in size.

In all the forms of burner, excepting that illustrated in Figs. 5, 6, 8 and 9, the fuel-feeder and its accessories can be removed by unscrewing the screw-cap and withdrawing the interior members. In the form illustrated in Figs. 5, 6, 8 and 9, the fastenings for the fuel-feeder are detached and removed by removing the screw-cap, and the fuel-feeder is removed at the flaring end of the casing.

Other modes of applying the principle of my invention may be employed for the mode herein explained. Change may therefore be made as regards the mechanism thus disclosed, provided the principles of construction set forth, respectively, in the following claims are employed.

Having thus described my invention, what I claim as new and desire to secure by Letters Patent, is:

1. A liquid fuel burner, comprising a transversely restricted longitudinal passage having an inlet for a diluent and forming

an atomizing and mixing chamber, and an expansible fuel-duct having when expanded a helical fuel inlet opening into such passage.

2. A liquid fuel burner, comprising a transversely restricted longitudinal passage having an inlet for a diluent and forming an atomizing and mixing chamber, and an expansible fuel-duct having when expanded a restricted helical fuel inlet opening into such passage.

3. A liquid fuel burner, comprising a transversely restricted longitudinal passage having an inlet for a diluent and forming an atomizing and mixing chamber, and an expansible fuel-duct forming one wall of said passage and having when expanded a helical fuel inlet into the same.

4. A liquid fuel burner, comprising a casing formed with a longitudinal chamber, and an expansible fuel-feeder longitudinally supported within such chamber to produce an atomizing and mixing chamber between it and the casing, said latter chamber having an inlet for a diluent and said fuel-feeder formed with an internal fuel-duct and when expanded with a helical continuous inlet from such duct into the atomizing and mixing chamber.

5. A liquid fuel burner, comprising a transversely restricted longitudinal passage having an inlet for a diluent and forming an atomizing and mixing chamber, and an expansible fuel-duct having when expanded an extended helical, automatically expansible and contractible fuel inlet opening into such passage.

6. A liquid fuel burner, comprising a transversely restricted longitudinal passage having an inlet for a diluent and forming an atomizing and mixing chamber, and an expansible fuel-duct having when expanded a restricted extended helical, automatically expansible and contractible fuel inlet opening into such passage.

7. A liquid fuel burner, comprising a transversely restricted longitudinal passage having an inlet for a diluent and forming an atomizing and mixing chamber, and an expansible fuel-duct forming one wall of said passage and having when expanded an extended helical, automatically expansible and contractible fuel inlet into the same.

8. A liquid fuel burner, comprising a transversely restricted longitudinal passage having an inlet for a diluent and forming an atomizing and mixing chamber, and an expansible fuel-duct forming one wall of said passage and having when expanded a continuous helical, automatically expansible and contractible fuel inlet into the same.

9. A liquid fuel burner, comprising a casing formed with a longitudinal chamber, and an expansible fuel-feeder longitudinally supported within such chamber to produce

an atomizing and mixing chamber between it and the casing, said latter chamber having an inlet for a diluent and said fuel-feeder formed with an internal fuel-duct and when 5 expanded with a continuous helical, automatically expandable and contractible inlet from such duct into the atomizing and mixing chamber.

10. A liquid fuel burner, comprising a casing formed with an axial bore having a nozzle-outlet at one end and a diluent inlet at the other end, and a fuel feeder axially supported in said bore to form an annular atomizing and mixing chamber and composed of a helix of wire forming a fuel duct and having one end closed and a fuel-inlet in the other end and said helix when expanded providing a continuous helical opening.

20. 11. In a liquid fuel burner, an atomizing and mixing passage therein and having means for introducing a diluent therein, and expansible means for discharging a supply of liquid fuel into said passage at continuously increasing distances from the admission point of the diluent.

12. In a liquid fuel burner, an atomizing and mixing passage therein and having means for introducing a diluent therein, and 30 a single means actuated and controlled by the pressure of the liquid fuel for progressively discharging said fuel into said passage.

13. In a liquid fuel burner, an atomizing and mixing passage therein and having 35 means for introducing a diluent therein, and expansible means for progressively bringing a continuous helical body of a fuel into contact with the diluent.

40. 14. In a liquid fuel burner, an atomizing and mixing passage therein and having means for introducing a diluent therein, and means for continuously and progressively admitting liquid fuel into said passage in 45 an unbroken continuity to commingle with the diluent therein.

15. In a liquid fuel burner, an atomizing and mixing passage therein and having 50 means for introducing a diluent therein, and means actuated by the pressure of the liquid fuel to form an extended opening for admitting the latter into said passage.

55. 16. In a liquid fuel burner, an atomizing and mixing passage therein and having means for introducing a diluent therein, and means for admitting a body of liquid fuel in helical form throughout substantially the length of said passage to commingle with the diluent passing therethrough.

60. 17. In a liquid fuel burner, an atomizing and mixing passage therein and having means for introducing a diluent therein, and an expansible liquid fuel feeder having when expanded a continuously extending spiral discharge opening into said passage.

18. A liquid fuel burner, comprising a casing having a bore therethrough, a helical spring having normally closed coils and extending in said bore to form a chamber between it and the wall of said bore, means 70 for supplying a diluent under pressure into said chamber, and means for supplying liquid fuel into said spring, the pressure of said fuel serving to expand said spring to admit fuel into said chamber.

19. A liquid fuel burner, comprising a casing having a bore therethrough, an axially expandible fuel-feeder providing a helical slot when expanded, said slot serving as a discharge-opening and said fuel feeder extending in said bore to form a chamber between it and the wall of said bore, means for supplying a diluent under pressure into said chamber, and means for supplying liquid fuel into said fuel-feeder, the pressure of 80 said fuel serving to expand said fuel-feeder to admit fuel into said chamber.

20. In a liquid fuel burner, a casing having a bore therethrough and an inlet for a diluent, and a fuel feeder in such bore and having a helical discharge port normally closed and adapted to be opened by the pressure of the fuel in the feeder for varying the area of said port and the quantity of fuel fed through the same.

21. In a liquid fuel burner, a casing having a bore therethrough, and an expandible tubular duct supported within said bore and forming with the wall thereof, an annular chamber and said duct being adapted to be 100 expanded by pressure of the fuel to form a helical fuel outlet for admitting the fuel into said annular chamber.

22. In a liquid fuel burner, a casing having an inlet and an outlet nozzle, and an expandible liquid-fuel feeder located within said casing to form a chamber surrounding it and having an inlet into its interior and when expanded having a circumferential and radially-directed and longitudinally 110 extending, contractible and expandible helical fuel inlet into said surrounding chamber.

23. In a liquid fuel burner, a casing having an outwardly flaring bore and an inlet for a diluent at the inner end of said bore, and an outwardly flaring expandible fuel-feeder supported within said bore to form an outwardly flaring annular atomizing and mixing chamber and formed when expanded with a longitudinal fuel duct having a helical fuel inlet into said chamber and a fuel-inlet at one end.

24. In a liquid fuel burner, a casing having an outwardly flaring bore and an inlet for a diluent at the inner end of said bore, 125 an outwardly flaring expandible fuel feeder supported within said bore to form an outwardly flaring annular atomizing and mixing chamber and having when expanded a helical and longitudinally extending fuel 130

inlet into said chamber, and an outwardly flaring core supported within said feeder to form a flaring annular fuel-duct between it and the feeder and having a fuel-inlet at its inner end.

25. In a liquid fuel burner, a casing having an outwardly flaring bore and an inlet for a diluent at the inner end of said bore, an outwardly flaring expandible fuel feeder supported within said bore to form an outwardly flaring annular atomizing and mixing chamber and having when expanded a helical and longitudinally extending expandible and contractible fuel inlet into said chamber, and an outwardly flaring core supported within said feeder to form a flaring annular fuel-duct between it and the feeder and having a fuel-inlet at its inner end.

26. In a liquid fuel burner, an atomizing and mixing chamber, means in said chamber for forming a continuous helical body of liquid of small width and of considerable extent in a longitudinal direction for feeding the liquid as the latter is atomized and removed, and means for passing a diluent over said body.

27. A liquid feeder composed of a helix of wire forming a liquid duct and having one end closed and the other end provided with a liquid inlet, the helix, when expanded, having a continuous helical opening for the discharge of the liquid therefrom.
